US00D395371S

United States Patent [19]

Sharpe

[11] Patent Number: Des. 395,371

[45] Date of Patent: Jun. 23, 1998

[54] TOOTHBRUSH AND TUMBLER HOLDER

[75] Inventor: Norton Sharpe, Los Angeles, Calif.

[73] Assignee: Franklin Brass Manufacturing Company, Rancho Dominguez, Calif.

[] Term: 14 Years

[21] Appl. No.: 63,599

[22] Filed: Jun. 25, 1996

Related U.S. Application Data

[63] Continuation of Ser. No. 41,010, Jun. 29, 1995, abandoned.

[51] LOC (6) Cl. 07-07
